CLAIM

The ornamental design for a tread for a shoe sole, as shown and described.

DESCRIPTION

FIG. 1 is a first perspective view for a tread for a shoe sole showing my new design;

FIG. 2 is a second perspective view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines showing the remainder of the shoe are for purposes of illustrating environmental structure only and form no part of the claimed design.
